UNITED STATES PATENT OFFICE.

GEORGE E. RUDNICK, OF BOSTON, MASSACHUSETTS.

DROP-COVER CHECK.

1,333,939.

Specification of Letters Patent. Patented Mar. 16, 1920.

Application filed March 18, 1919. Serial No. 283,320.

To all whom it may concern:

Be it known that I, GEORGE E. RUDNICK, a citizen of the United States, and a resident of Roxbury, Boston, county of Suffolk, 5 and Commonwealth of Massachusetts, have invented an Improvement in Drop-Cover Checks, of which the following description, in connection with the accompanying drawings, is a specification, like characters on the drawings representing like parts.

This invention relates to cover supporting and checking means for retaining in open position, and checking or controlling the closing action of a top or cover for talking 15 machines, music boxes, and similar cabinets.

In the drawings of the embodiment of my invention selected for illustration and description,

Figure 1 is a side elevation of a conventional form of talking machine cabinet with my novel cover check in position thereon;

Fig. 2, a detail plan and partial section on the line 2—2 Fig. 1;

Fig. 3, a partial sectional view on the 25 line 3—3 Fig. 1;

Fig. 4, a similar view of a modified form of construction;

Fig. 5, a detail of a modified form of construction of the hinge for the supporting 30 rod;

Fig. 6, a detail of a modified form of the cylinder construction;

Fig. 7, a vertical section on the line 7—7 Fig. 6, and

Fig. 8, a modified form of cylinder and supporting rod construction.

My novel check comprises, Figs. 1, 2, 3, a cylinder 1 of suitable material as metal, with a flange 2, suitably mounted on the shelf 3 40 of the cabinet 4. This cylinder is provided at or near its lower end with an air valve 5, comprising a seat 6 with ports 7 therethrough, and a stud 8.

This stud may be secured by a nut 9 on 45 its lower end and it carries a head 10 at its opposite end. Beneath the head and seated against it is a spiral spring 11 which acts to press down upon a disk 12 preferably of flexible material as leather, and thereby 50 cause it to normally close the ports 7. The cylinder may also have a port 7^a if desired although it is not necessary.

In its opposite and upper end the cylinder carries a plunger 13 of any suitable material as metal with a washer 14 as of leather. To the end of the plunger Fig. 1,

is pivoted or otherwise loosely connected a cover supporting rod 14', the upper end of which is movably connected, as by a screw 15, to a hinge or plate member 16, secured as by screws to the cover 17. In this case the member 14' is bent to enable it to clear the edge of the cylinder 1, as it descends. 60

For retaining the plunger 13 and rod 14' in elevated position I provide a novel catch 65 Figs. 2, 3, comprising a plate 17 with an elongated aperture 18 therein, which receives the plunger 13. When the plunger is in raised position Fig. 1, the straight edge of the aperture 18 rests within a slot 19 in 70 the side of the plunger and thereby supports it.

The catch 17 Figs. 2, 3, is provided with a shank 20 which extends through the side of the cabinet 4 and carries a knob 21 at its 75 end. Between the knob 21 and the cabinet wall, and countersunk at 22 therein, is a coil spring 22^a acting normally to retain the plate in plunger engaging or extended position.

The catch is also provided with a neck 23 having a slot 24 through which is inserted a screw or pin 25 which acts not only to prevent lateral movement of the catch 17, but the head of the screw acts to keep the 85 catch down adjacent the surface of the shelf 3, while permitting the desired movement thereof. 80

Obviously when raising the cover and plunger the latter will slide freely against 90 the edge of the catch 17 until the latter engages the slot 19 when the upward travel of the plunger will be arrested and of course it will be prevented from descending by the same means.

When it is desired to lower the cover, one simply pushes in on the knob 21 disengaging the catch 17 from the slot 19 and the cover will descend slowly as the air leaks out beneath the disk 12, and escapes by the 100 port 7^a if the latter is provided.

In Fig. 4 is shown a modification wherein the catch 17 engages a lug 26 on the side of the rod 14, resting between it and top of the plunger 13. 105

In Fig. 5 I show a modified form of hinge member 16 wherein the end of the rod 14' is drilled to receive a rod 27 extended between the outstanding arms 28 on the member 16, the rod 14' sliding on the rod 27 as 110 is necessary for it to travel freely in the cylinder 1.

In Fig. 6 I have illustrated a further modification wherein the rod 14 has a rigid connection with the plunger 13, and the cylinder 1 is pivoted at a fixed point in the plate 16 by trunnions 29 which are seated in depressions in the plate 30 on the shelf 3 and which permit the cylinder to swing thereon as is necessary to accommodate the movement of the support 14. An upper plate 31 serves to retain the trunnions in position.

In Fig. 8 I show also a further modification in which the cylinder 1 is positively mounted at its lower end, as by a screw 32 and the plunger also has rigid connection 15 with the member 14.

As the plunger descends the cylinder obviously will swing on its pivot 32 so far as is necessary to permit the cover to close.

In this case, also I show an additional 20, supporting member 33 for the cover which may be controlled by a catch 17 as in the other instances referred to.

Claims:

1. Means for checking the closing movement of a cabinet cover comprising a cylinder having a valve, a plunger in the cylinder, a catch adjacent the cylinder to engage the plunger and hold it in outward position, and a supporting member connecting the 25 plunger with the cover.

2. Means for checking the closing movement of a cabinet cover comprising a cylinder having a valve, a plunger therein, a catch comprising a support engaging plate, 35 means normally holding the plate in plunger supporting position, and means operable from the outside of the cabinet for releasing the plunger to permit the cover to close.

3. Means for checking the closing movement of a cabinet cover comprising a cylinder having a valve, a plunger in the cylinder, a catch adjacent the cylinder to engage the plunger, a plate on the cover, and a supporting member connecting the plunger 40 slidably with the plate.

4. Means for checking the closing movement of a cabinet cover comprising a cylinder having a valve, and movably connected to the cabinet, a plunger in the cylinder, a 50 catch adjacent the cylinder to engage the plunger and a supporting member connecting the plunger with the cover.

5. Means for checking the closing movement of a cabinet cover comprising a cylinder having a valve, and movably mounted 55

upon the cabinet, a plunger in the cylinder, a supporting member connecting the plunger with the cover, an auxiliary cover supporting member for the cover and a catch operable from the outside of the cabinet to 60 engage the auxiliary member and support the cover.

6. Means for checking the closing movement of a cabinet cover comprising a cylinder, a valve therein, a plunger also therein, 65 a cover supporting rod connecting the cover and plunger, and a catch on the cabinet for holding the plunger in withdrawn position and the cover open.

7. Means for checking the closing movement of a cabinet cover comprising a cylinder, a valve therein, a plunger also therein, 70 a cover supporting rod connecting the cover and plunger, and a catch on the cabinet comprising a plate with a plunger receiving aperture, a neck on the plate extended through the cabinet wall, and a spring acting to retain the plate in locking engagement with the extended plunger to support the cover.

8. Means for checking the closing movement of a cabinet cover comprising the cabinet 4 with a shelf 3 and cover 17 therefor, a cylinder 1 mounted on the shelf, and having the valve 6, and plunger 13, the rod 14' connecting the plunger with the cover, and a catch 17 having a plunger receiving aperture 18, adapted to engage the slot 19 in the plunger, said catch having the neck 23 with a slot 24 therein, the shank 20, spring 22^a 90 thereon to retain the catch in extended position to support the plunger and cover.

9. Means for checking the closing movement of a cabinet cover comprising the cabinet 4 having a shelf 3 and cover 17, a cylinder 1 pivoted to said shelf adjacent its upper end, the valve 6 for the cylinder and a plunger 13 therein, the supporting rod 14' connecting the plunger and the cover, and a catch 17 having the rod receiving aperture 18, and adapted to engage the rod 14' 95 to hold the rod and cover in raised position, said catch having the neck 22 and the slot 24 therein, shank 20 and spring 22^a for retaining said catch in locking engagement 100 with the rod.

In testimony whereof I have signed my name to this specification.

GEORGE E. RUDNICK.
